[57] **CLAIM**

The ornamental design for a lantern, as shown and described.

DESCRIPTION

FIG. 1 is a perspective view thereof with a handle in a first position;

FIG. 2 is a front elevational view thereof with the handle in the first position;

FIG. 3 is a right side elevational view thereof with the handle in the first position;

FIG. 4 is a rear elevational view thereof with the handle in the first position;

FIG. 5 is a left side elevational view thereof with the handle in the first position;

FIG. 6 is a top plan view thereof with the handle in the first position;

FIG. 7 is a bottom plan view thereof with the handle in the first position;

FIG. 8 is a top plan view thereof with the handle in a second position; and,

FIG. 9 is a left side elevational view thereof with the handle in the second position.

The perspective view, front elevational view, rear elevational view, right side elevational view and bottom plan view of the lantern with the handle in the second position have been omitted because these views are readily apparent from the views illustrated in FIGS. 8 and 9.
